UNITED STATES PATENT OFFICE.

GEORGE HILLARD BENJAMIN, OF NEW YORK, N. Y.

DRYING APPARATUS.

1,172,576.

Specification of Letters Patent. Patented Feb. 22, 1916.

Application filed March 18, 1915. Serial No. 14,665.

To all whom it may concern:

Be it known that I, GEORGE HILLARD BENJAMIN, a citizen of the United States, residing at New York city, in the county 5 and State of New York, have invented a certain new and useful Improvement in Drying Apparatus, of which the following is a specification.

My invention relates to certain new and 10 useful improvements in apparatus adapted for drying articles of vegetable, animal and mineral origin.

The object of my invention is the construction of a device into which the articles 15 to be dried can be conveniently introduced, and from which they may be readily removed without involving expensive handling, and when in said device, subjected to the uniform action of large volumes of 20 heated air for the purpose of removing moisture, or otherwise acting upon said bodies to produce results as desired.

In a former application for patent, to wit, Serial No. 854,598 filed August 1st, 25 1914, I have described a drying apparatus consisting of a series of cells containing trays upon which the materials to be dried are placed, a hot air inlet flue, an outlet flue, and a flue arranged in proximity to the 30 cells provided with a series of dampers which may be moved mechanically to vary the vertical depth of the air currents through the cells.

My present application involves the same 35 general idea, modified in that the cells, instead of being separated, are combined and arranged to be given a circulatory movement as regards the incoming heated air currents, which air currents, as in my former application, are arranged to be introduced at different levels at successive 40 periods, through the combined cells.

The particular advantage of the present arrangement over that described in my former 45 application, is that by combining the cells, the capacity of the apparatus for a definite floor space, is increased, is made more effective, and more rapid drying is brought about owing to the relative movement 50 of the material and the incoming air currents, and further, in that the modified device permits of the automatic feeding of

the material to be dried, when such material is in the form of cossettes, grains or granules, as also the automatic discharge of the 55 materials from the apparatus, thereby avoiding all costly handling.

The accompanying drawings, which are in a sense diagrammatic (as they are not intended to illustrate all the details of construction of my improved apparatus, but only such as are necessary to a clear understanding of the different features of construction and their relation) will serve to illustrate my invention, in which:

Figure 1 is a plan view and horizontal section taken on the line I—I of Fig. 2. Fig. 2 is an elevation and vertical section taken on the line II—II of Fig. 1. Fig. 3 is a vertical section taken on the line III—III 70 of Fig. 1. Fig. 4 is a vertical section taken on the curved line IV—IV of Fig. 1. Fig. 5 is an elevation and vertical section taken on the line V—V of Fig. 1, the view 75 at the left of the figure showing the discharge scrapers in their lowest position. Fig. 6 is a side elevation and partial section illustrating the mechanism for collectively actuating the scrapers and illustrating the scrapers in the position which 80 they would occupy to remove a portion of the material situated upon the disks. Fig. 7 is an elevation and vertical section taken on the line VII—VII of Fig. 8 and showing a modification of the construction shown 85 in Figs. 1 and 2. Fig. 8 is a view corresponding to Fig. 1 and taken on the line VIII—VIII of Fig. 7.

Referring first to Figs. 1 to 5 inclusive, 90 5 indicates a shaft supported in a suitable bearing 6. At the bottom of the shaft is a worm gear 7, which cooperates with a worm 8, adapted to be driven by any suitable motor 9. Located upon and attached to the shaft so as to rotate with it, are a series of 95 disks 10. These disks are formed by means of spokes 11, which at their outer ends support a perforated plate 12. 13—14 represent respectively, the horizontal and vertical members of an inner casing 15, which is 100 mounted on and is moved with the disks 10. The horizontal portions of this casing are provided with a circular bearing rail 16, which coacts with the roller bearings 17 to

support the casing. 18-19 represent respectively, horizontal and vertical portions of an exterior casing 20, which surrounds the apparatus.

5 Located on the outer periphery of the vertical portion 14 of the inner casing 15, are a series of projections 21 which serve to support a series of rings 22. The rings 22, as will hereafter be described, are stationary, and the projections 21 serve as supporting bearings for these rings, the projections 21 moving with the disks 10 and inner casing 15.

10 23 (Fig. 1) indicates a series of air deflectors, secured at one end to the vertical wall 19 of the exterior casing 20, and at the other end to the rings 22. The air deflectors 23 are shown as placed at an angle, and have for their purpose to cause the incoming air currents to move forward in a direction opposite to the movement of the disk, the movement of the air current being indicated by a single arrow, and the movement of the disk being indicated by double arrows, as shown in Fig. 1. The air deflectors 23 have fixed positions and are of a vertical height to close the space over the material (indicated at 24, Fig. 2) on the disk 10, but having their bottoms stationed 25 over the disk to permit the material 24 to move under the air deflectors 23.

15 Situated at one side of the apparatus, is an air inlet duct 25 provided with controlling dampers 26, which may be operated by 30 a rod or other suitable device 27.

20 28 indicates dampers which are pivoted in vertical walls 29 of the air inlet duct. Connected to these dampers are arms 30, links 31, and a bell crank 32, under control 40 of a link 33, connected to a crank 34 secured to a shaft 35, on which is a worm gear 36 adapted to be moved by worm 37 on shaft 38 connected to the source of power through pulley 39. By rotating the shaft 45 38, dampers 28 will be alternately moved to take certain defined positions, for instance: With the dampers in the position shown in Fig. 2, air entering the inlet duct passes over all of the disks; with the 50 dampers in the position shown in Fig. 7, at the right, incoming air passes over the upper disk; with the dampers in the position shown at the left of Fig. 7, incoming air passes over four of the disks. The purpose of arranging the dampers as shown, is to change at successive periods, the horizontal movement of the incoming air currents and thus provide for an even distribution of air through the apparatus.

55 60 I have not entered into a detailed description of the mechanism for controlling the dampers, as the same has been fully set forth in a prior application filed by me, to which I have previously referred.

65 40 indicates an air outlet duct. It will

be observed that the air inlet duct 25 is situated at one side of the air deflectors 23, and the air outlet duct 40 at the other side. Consequently, the air entering the apparatus will traverse a circuitous path from 70 the air inlet duct, around the apparatus and out of the air outlet duct, as indicated by the single arrows. Situated in the air outlet duct 40 are dampers 41, which may be simultaneously operated by means of suitable levers indicated at 42 (Fig. 1). By reason of the dampers 41, the pressure of air within the apparatus may be varied.

75 43 indicates a discharge duct shown in Fig. 1 as situated near the air inlet duct, 80 and at the same side as the air deflectors 23. Mounted on shafts 44 are discharge scrapers 45, which may be actuated by means of arms 46 connected by links 47, and held in any desired position by engagement of a 85 pin 48 with one of a series of holes formed in the link, and a hole formed in the wall 19. The shafts 44 have their bearings at one end in the vertical portion 19 of the exterior casing 20, and at the other end in 90 the rings 22. The scrapers are shown as inclined.

95 In Fig. 4 the scrapers are shown in their upper or inoperative position; in Fig. 5, at the left of the drawing, in their operative or discharging position, and in Fig. 6, in a half-way position to scrape off and discharge a layer of definite thickness from the top of the material on the disk 10, it being within the contemplation of my invention to either discharge the material from the disk as a whole with the discharging scrapers in the lowest position, or as layers, in which latter case the scrapers are gradually moved down as the successive 100 layers are removed. It will be understood that as the disks rotate in the direction of the double arrows, the material on the disk is brought into contact with the scrapers, passes over the scrapers, and out of the 110 discharge duct 43.

115 In Fig. 3 is shown an apparatus for feeding the material to be dried, on to the disks. The device consists of vertical passages 49, through which the material to be dried is fed. Vertical passages 49 communicate through inclined passages 50, with horizontal tubes 51, each extending through the vertical wall 19 and supported at the inner end in a ring 22. When desired, the inclined passages 50 may be closed by means of a valve 52. Mounted on the exterior of each tube 51 is a movable tube 53. At the outer end of the tubes 53 is a gear 54, in mesh with a gear 55 on a shaft 56, on the opposite end of which is a gear 57 driven by any suitable source of power. Formed through the body of each of the tubes 53, are helical slots 58. Each stationary tube 51 is provided with a longitudinal slot 59.

In each of the stationary tubes 51 is journaled a shaft 60 having a worm 61 secured thereto and located at the end of the tube which communicates with the passage 50.

5 Located on the outer ends of the shafts 60 are gears 62 in mesh with a gear 63 on shafts 56.

The operation of this portion of the device is as follows: The material fed down 10 the vertical passage 49, the valve 52 being open, will pass through the inclined passages 50 into the tubes 51, being progressively fed into the tubes by the worm 61, to be discharged through the slots 59, progressively 15 across the disk as the helical slot 58 moves over and opens the slot 59. In order to insure an even distribution, provision is made in Fig. 1 for a duplicate feeding apparatus, and for the reason that as the area 20 of the inner periphery of the disk is less than that of the outer periphery of the disk, if a single feeding device were used, more material would be discharged from the inner periphery of the disk than from the 25 outer periphery, but with the arrangement shown, the delivery is equalized.

64 indicates shafts carrying plates 65, and having bearings respectively in the vertical portion 19 of the exterior casing 20 and in 30 the rings 22. The shafts are provided with arms 66 and a link 67 for moving them. The object of this device is to provide, when the device is in the operative position shown at the right of Fig. 4, for leveling the material 35 on the disk 10, as it is delivered thereon.

In treating certain materials, especially those which evolve a large amount of moisture or gases in the drying operation, it is usual to provide means for either drawing 40 off the evolved gases, or injecting highly heated air.

68 indicates pipes arranged horizontally along the outer periphery of the apparatus. From these pipes 68, lead perforated pipes 45 69. It will be observed, on reference to Fig. 2, that these pipes are located above the disks 10; consequently, the perforated portion 12 of each disk is between two pipes 69, thus each pair of pipes will serve to extract moisture 50 from the top and bottom of the material on the perforated disks, or apply air currents thereto. The pipes 69 are mounted in bearings 70 in the vertical portion 19 of the exterior casing 20, and in the rings 22, 55 the purpose of which arrangement is to allow ready removal of the pipes 68 and 69.

In Fig. 1 the pipes are all shown as located over that portion of the disk which is farthest away from the air inlet duct and air outlet duct, and for the reason that the evolution of gas or other bodies is greater at this point, or conversely, the temperature of the incoming air least effective.

Connected through the pipes 68 through a vertical pipe 71 and valves 72, is a vacu-

um pump 73, and an air pressure pump 74. Manifestly a single pump may be used, to be rotated in one direction when used as a vacuum pump, and in the other direction when used as an air pump.

70

Referring now to Figs. 7 and 8 the construction described is the same, with the following exception: The disk is divided into four sections or air chambers, marked for the purpose of reference, A, B, C, D, and each division has an air inlet duct 25 and an air outlet duct 40, the air outlet duct in Figs. 7 and 8 being located at the center of the disk instead of at the periphery of the disk as in Fig. 1. In each of the air outlet ducts is a damper 41'. It will be understood that the air entering through the air inlet duct 25 will pass through the spaces A, B, C, D, respectively, and then out through the air outlet ducts 40, as controlled by the dampers. In the construction shown in these figures, the pipes 69 are placed in each division A, B, C, D.

75

I wish it understood that I do not limit myself in any wise to the number of pipes 90 69 as shown in Figs. 1 or 8, or to their exact position, as they may be changed to suit different requirements.

In Fig. 7 the perforated plates 12 are supported at one edge on projections 75 secured to a cylinder 76 (Fig. 8) projecting up from the annular base plate 77, and at the other edge by rings 78 secured to the inner periphery of the exterior casing 20, the plates 12 being provided with rollers 79 which move over the rings 78. The vertical wall of the cylinder 76 is provided with ports 80, through which the air passing over the plates 12 finds entrance into the outlet 100 duct 40.

95

In the construction shown in Fig. 7, the annular base plate 77 is mounted on rollers 81 which travel on rails 82. Motion is communicated to the base plate and the disks through the motor 9, gear 83 and rack 84 at 105 the bottom of the base plate.

110

With the construction shown in Fig. 8, but a single feeding apparatus is required, for it will be seen that the leveling plate 65 extends angularly across the active surface of the revolving plates 12, and therefore serves while leveling the material, to move the excess thereof from the center toward the periphery of the plates 12. Whereas in Fig. 115 1 the leveling plate extends directly across the active surface of the disk 10, or in other words, one is disposed tangentially, while the other is disposed radially.

115

85—86 indicate air deflectors projecting 120 into the air spaces, which have for their object to divert the current of air inwardly.

120

I wish it understood that I may use any type of air deflectors, placed respectively along the inner and outer periphery of the 130 air channel,

I wish it also understood that I may place the air deflectors in any position which may be found convenient.

The operation of my device is as follows: 5 The material to be treated is fed onto the disk, the disk being in motion in the direction of the double arrow. As it is fed on, it is leveled and moves toward the incoming air current from the air inlet duct. Mani- 10 festly, the air with which the material first comes in contact, is that containing the greatest percentage of moisture, as the material is then approximately opposite the air outlet duct. As the disk moves, the ma- 15 terial is gradually brought into contact with warmer and drier air, until it reaches the air inlet. The material then passes under the air deflector 23, and is again moved through the air current. This op- 20 eration is continued until the required percentage of moisture has been removed. When this point is reached, the scraper op- 25 posite the inlet duct is turned down, and as the disk rotates, a certain portion of the dried material comes in contact with the scraper and is diverted into the delivery duct; or the scraper being wholly turned down, all of the material is scraped off and diverted to the delivery duct. Where it is 30 desired to exhaust a portion of the air before reaching the air outlet, the vacuum pump may be actuated and the air current ex- 35 hausted through pipes 68—69, or conversely, where it is desired to introduce hot air, it may be delivered through the air delivery pump and pipes 68—69.

I wish it understood that I do not limit myself to the specific features of construction herein set forth, as I believe myself to 40 be the first to describe an apparatus consisting of a series of rotating disks on which the material to be dried is placed, and in which the drying operations are carried on during the time that the material to be dried 45 and the air currents to effect the drying, are moved in opposite directions as regards each other, and where the movements may be continued for the required length of time without changing the material to be dried from the position in which it is originally placed.

Having thus described my invention, I claim:

1. In a drier, the combination of a series 55 of horizontally arranged superposed rotatable disks, a casing for said disks, means whereby air currents will move over said disks in a direction opposite to the direction of movement of said disks, means for feeding material to be treated on to said disks, means for discharging the treated material from said disks, and means for giving motion to said disks.

2. In a drier, the combination of a series 60 of superposed rotatable disks, a casing inclosing said disks, a series of air deflectors,

means for feeding material to be treated on to said disks, an air inlet duct, an air outlet duct, means in said air inlet duct for varying the vertical depth of the incoming air currents, means in said air exit duct for varying the area of the duct, a discharge duct, adjustable means whereby the material on the disks will be directed to the discharge duct, and means for giving motion to the disks. 75

3. In a drier, the combination of a series of horizontally arranged superposed rotatable disks, a series of air deflectors arranged to deflect the air forward in a direction opposite to the rotation of the disks, a casing 80 inclosing said disks and deflectors, an air supply duct, an air exit duct, means for feeding material to be treated onto the disks, means for discharging the treated material from the disks, and means for giving rotary motion to the disks. 85

4. In a drier, the combination of a series of horizontally arranged superposed rotatable disks, a casing inclosing said disks, an air supply duct, an air exit duct, means for supplying additional air currents to the space intervening between any two superposed disks, means for feeding material to be treated on to the disks, means for discharging the treated material from the 95 disks, and means for giving rotary motion to the disks.

5. In a drier, the combination of a series of superposed perforated rotatable disks, means whereby air currents will be caused 100 to move over and above said disks in a circular direction, and means whereby air currents will be caused to move through said disks in a perpendicular direction.

6. In a drier, the combination of a series 105 of superposed rotatable disks, a casing inclosing said disks, means for causing air currents to flow over said disks and means for causing said air currents to flow in a horizontal direction and opposite to that of the rotation of the disks, together with means for rotating the disks.

7. In a drier, the combination of a series 110 of superposed rotatable disks, a casing inclosing said disks, a plurality of air supply ducts, a plurality of air exit ducts, means for successively varying the vertical depth of the incoming air currents, and means for varying the area of the air exit ducts. 115

8. In a drier, the combination of a series 120 of superposed disks, a casing inclosing said rotatable disks, an air supply duct, an air exit duct, a series of perforated pipes arranged between pairs of the disks, an air pump and a vacuum pump connected to said perforated pipes, means for feeding the material to be treated to the disks, means for discharging the treated material from the disks, and means for imparting rotary motion to the disks. 125 130

9. In a drier, the combination of a series of superposed rotatable disks, a casing inclosing said disks, an air supply duct communicating with the interior of said casing, means in said air supply duct for varying the vertical depth of the air current transmitted to the interior of the casing, an air exit duct communicating with the interior of said casing, a damper in said air exit duct, together with means for imparting motion to the disks. 5
10. In a drier, the combination of a series of superposed rotatable disks, a casing inclosing said disks, an air supply duct and an air exit duct communicating with the interior of said casing, a series of air deflectors, one arranged over each of said disks and disposed at an angle whereby the incoming air currents will pass over the surface of the disks before leaving the apparatus through the air exit duct, and means for imparting rotary motion to the disks. 15
11. In a drier, the combination of a series of superposed disks, a casing inclosing said disks, an air supply duct communicating with the interior of said casing, means in said air supply duct for varying the vertical depth of the air current transmitted to the interior of the casing, an air exit duct communicating with the interior of said casing, a damper in said air exit duct, a series of means over each disk for feeding material to the disks and distributing it thereon, a series of means, one over each disk, adapted to direct the treated material from the disk to a discharge duct, a discharge duct communicating with the interior of the casing, together with means for imparting rotary motion to the disks. 20
12. In a drier, the combination of a series of superposed disks, a casing inclosing said rotatable disks, an air supply duct and an air exit duct communicating with the interior of said casing, means for feeding the material to be treated to the disks, a discharge duct through which the treated material is carried from the disks, a series of air deflectors and a series of scrapers, said scrapers disposed to direct the treated material on the disks to the discharge duct, and means for imparting rotary motion to the disks. 25
13. In a drier, the combination of a series of superposed disks, a casing inclosing said rotatable disks, an air supply duct and an air exit duct communicating with the interior of said casing, means for supplying an additional air current over a portion of each disk, a series of air deflectors, means for feeding the material to be treated on to the disks, means for discharging the treated material from the disks, a discharge passage common to all the disks, and means for imparting rotary motion to the disks. 30
14. In a drier, the combination with a series of horizontally rotating disks of means for feeding material on to the disks, said means comprising a tube having a longitudinal slot at the bottom, a worm conveyer working in said tube, a second tube provided with a helical slot arranged over said first named tube, and means for giving motion to said conveyer and to said second named tube. 35
15. In a drier, the combination of a series of superposed rotatable disks, a casing inclosing said disks, an air supply duct having a vertical depth corresponding to that of the casing and located at one side of the casing, an air exit duct having the same vertical depth as the casing and placed in juxtaposition to the air inlet duct and at the same side of the casing, means for varying the vertical depth of the incoming air currents, means whereby the incoming air currents will move circularly over the disks from the inlet duct to the exit duct, and means for imparting motion to the disks in a direction opposite to that of the incoming air currents. 40
- 45

In testimony whereof, I affix my signature, in the presence of two witnesses.

GEORGE HILLARD BENJAMIN.
